(57) **CLAIM**

We claim the ornamental design for a combined phone and base therefor, as shown and described.

DESCRIPTION

FIG. 1 is a perspective view of a combined phone and base therefor, showing our new design;

FIG. 2 is a front elevational view thereof;

FIG. 3 is a rear elevational view thereof; and

FIG. 4 is a left side elevational view thereof;

FIG. 5 is a right side elevational view thereof.

FIG. 6 is a top plan view thereof;

FIG. 7 is a bottom plan view thereof;

FIG. 8 is a partially exploded, front-left perspective view thereof, the phone and the base shown separated for clarity of disclosure; and,

FIG. 9 is a partially exploded, front-right perspective view thereof, the phone and the base shown separated for clarity of disclosure.

The broken lines in the drawings depict parts of combined phone and base therefor that form no part of the claimed design.
